UNITED STATES PATENT OFFICE

2,665,847

STEAM FLOW CONTROL SYSTEM

Robert F. Schaub, Chicago, Ill., assignor to Fred H. Schaub Engineering Co., Inc., Chicago, Ill., an Illinois corporation

Application June 2, 1950, Serial No. 165,852

2 Claims. (Cl. 237—67)

1

This invention relates to steam flow control systems and more particularly to systems for controlling the supply of steam to a plurality of steam using units.

It has been proposed heretofore to circulate an excess quantity of steam through the majority of the units in an installation and to utilize the steam discharged from such units to operate the remainder of the units in the installation. Such systems have employed accumulators to receive the discharge from the primary units and separate the steam therein from the condensate. One such system is shown, for example, in the copending application of Fred H. Schaub, Serial No. 234, filed January 2, 1948, now matured into Patent No. 2,532,951.

The present invention has for one of its objects the simplification of a system of this type to eliminate the accumulator and to effect the separation of steam and condensate discharged from the primary units in the steam header.

Another object is to provide a steam flow control system including a relatively large horizontal return header for the primary units equipped with a trap to prevent the discharge of steam therefrom in which the steam for operating the secondary units is drawn off directly from the return header.

The above and other objects and advantages of the invention will be more readily apparent when read in connection with the accompanying drawings, in which the single figure is a diagrammatic view of a steam flow control system embodying the invention.

In the system as illustrated there are a plurality of primary steam consuming units 10 and a secondary steam consuming unit 11 which may be identical with the primary units. The system of the present invention is applicable to many different types of units but is particularly applicable to control of the steam through a plurality of ironers in laundries and the like. For purposes of the present description the steam consuming units are, therefore, assumed to be ironers.

Steam is supplied to the primary ironer units 10 to heat them from a steam supply manifold 12 leading from a suitable boiler. The primary units are separately connected to the manifold through pipes 13 controlled by valves 14 so that one or more of the ironers may be shut off when desired. Discharge from the ironers is through discharge pipes 15 which contain restricting orifices 16 which tend to limit the flow through the primary units. The orifices 16 are connected

5 through check valves 17 to a horizontal return header 18 which, as illustrated, is of relatively large diameter. The header 18 runs adjacent the series of ironer units and is connected at one end to a trap 19 which will prevent the flow of steam from the header while permitting liquid condensate to flow to a return pipe 21 which will return it to the boiler. Preferably, the header 18 turns downward slightly to enter the trap 19, as indicated at 22, so that condensate accumulating in the header will be drained quickly into the trap and the header will at no time be completely filled with condensate.

10 The secondary unit 11 is connected by a pipe 23 to the top part of the return header 18 adjacent to the trap 19. Discharge from the secondary unit 11 is through a trap 24 which will pass condensate but will substantially prevent the passage of steam into the condensate return pipe 21.

15 In operation of the system, when steam is supplied to the primary units, a mixture of steam and condensate will be discharged therefrom through the orifices 16 into the return header. This mixture will tend to flow toward the trap and will separate by gravity with the steam rising to the top of the return pipe and the condensate flowing along the bottom of the pipe into the trap. The steam from the header will flow into the secondary unit 11 to heat it and condensate from the secondary unit will be discharged through the trap 24. While a secondary unit has been shown, it will be understood that one or more secondary units may be 20 employed so that their capacity will be such as to use all of the steam passing through the return header. In this way a continuous flow of steam is maintained through the primary units to prevent accumulation of condensate therein so that they are effectively heated. Excess steam 25 passing through the primary units is utilized in the secondary units for their proper operation so that there is no waste of steam. At the same time an extremely simple apparatus is employed 30 so that separation of the condensate and live steam from the primary units is effected in the return header.

35 While one embodiment of the invention has been shown and described in detail herein, it will be understood that this is illustrative only and is not to be taken as a definition of the scope of the invention, reference being had for this purpose to the appended claims.

What is claimed is:

55 1. A steam flow control system comprising a

plurality of steam using units, a steam supply header, conduits connecting a majority of said units directly to the header, a relatively large substantially horizontal tubular return header extending adjacent to the units, conduits connecting said majority of the units to the return header and each including a flow control restriction, trap means connected to one end of the return header to prevent discharge of steam therefrom while permitting discharge of condensate, and a steam connection from upper part of the return header adjacent to the trap to the remainder of the units.

2. A steam flow control system comprising a plurality of steam using units, a steam supply header, conduits connecting a majority of said units directly to the header, a relatively large substantially horizontal tubular return header extending adjacent to the units, conduits connecting said majority of the units to the return 15

header and each including a flow control restriction, trap means connected to one end of the return header to prevent discharge of steam therefrom while permitting discharge of condensate, a steam connection from the upper part of the return header adjacent the trap means to the remainder of the units, and separate trap means connected to the remainder of the units to prevent discharge of steam therefrom while 10 permitting discharge of condensate.
